(57) **CLAIM**

The ornamental design for a cutter for food products, as
shown and described.

DESCRIPTION

FIG. 1 is an isometric view of a cutter for food products.
FIG. 2 is another isometric view of the cutter for food
products of FIG. 1.

FIG. 3 is a top plan view of the cutter for food products of
FIG. 1.

FIG. 4 is a bottom view of the cutter for food products of
FIG. 1.

FIG. 5 is a front elevation view of the cutter for food
products of FIG. 1.

FIG. 6 is a rear elevation view of the cutter for food products
of FIG. 1.

FIG. 7 is a left side elevation view of the cutter for food
products of FIG. 1.

FIG. 8 is a right side elevation view of a cutter for food
products; and,

FIG. 9 is a cross-sectional front elevation view of the cutter
for food products of FIG. 1, taken on the line 9-9 in FIG. 3.
Portions of FIGS. 1 through 9 are shown in broken lines and
dash-dot-dash boundary lines illustrating portions of the
article that form no part of the claimed design.

1 Claim, 9 Drawing Sheets
